SHOE AND METHOD OF MAKING SAME

Edward Quinn, Brooklyn, N. Y., assignor to The
Del-Mac Shoe Process Corporation, New York,
N. Y.

Application December 17, 1935, Serial No. 54,797

5 Claims. (Cl. 36—68)

My invention relates to shoes and shoemaking. It has long been the custom in making fine shoes to construct the heavy counter and toe stiffeners or reinforcements of sheet material, such as leather, which are given shape by lasting them into the shoe in a wet condition and then permitting them to dry and shrink against the last. If the counter stiffener is adequately heavy to support the heel and quarter sections of the upper, when the shoe is worn the stiffener tends, by reason of its resiliency under the damp heat of the foot, to return to its original shape and the shoe becomes distorted, breaks down, and does not conform to the foot. If the stiffeners are less than amply heavy, they lack the strength to afford proper support and distortion is again the result. Because of this many shoemakers have adopted inferior materials which are stiff and less comfortable to the wearer than leather or fibre reinforcements.

A principal object of my invention, therefore, is to provide an improved shoe having a fibrous counter reinforcement which will conform closely to the last in manufacture and be strong and comfortable and hold the shape of the last in the finished shoe. Another object is to provide a shoe having an improved toe construction.

Also, inasmuch as toe and counter stiffeners are sold as articles of independent manufacture, a further object of my invention is to provide counter and toe reinforcements of improved construction. Other and further objects will appear from the following specification.

Referring to the drawings which form a part of this specification:

Figure 1 is a plan view on a reduced scale of a counter blank prepared in accordance with my invention.

Figure 2 is a sectional view taken on line 2—2 of Figure 1.

Figure 3 is a fragmental section similar to Figure 2 but drawn on a greatly enlarged scale.

Figure 4 is a cross sectional view taken on line 4—4 of Figure 1.

Figure 5 is a plan view of a blank prepared in accordance with my invention for stiffening the toe portion of a shoe.

Figure 6 is a perspective view showing the counter portion of a shoe upper, together with its lining, and illustrates the manner in which the counter blank may be inserted between the upper and lining preparatory to lasting the shoe.

Figure 7 is a perspective view of a last on which the shoe parts, including my improved reinforcements, have been assembled, the upper being

broken away at a quarter section of the shoe to disclose the relationship of the several parts.

Figure 8 is a side elevation of my improved shoe, the rear portion being shown in section and the upper being broken away over the toe tip to 5 reveal my improved toe construction.

Figure 9 is a fragmental section on a greatly enlarged scale illustrating in exaggerated proportions the form of the counter stiffener in the finished shoe.

In carrying out my invention I utilize an amply heavy leather or fibre counter blank 10 of conventional variety and of a configuration proper for the shoe into which it is to be assembled, the margins 11 of the blank being skived in the usual 15 manner. The size of the blank, however, is somewhat smaller than would ordinarily be required. I then weaken the blank over the areas which normally would be subjected to the greatest strain in the lasting operations. To do this I prefer 20 to form slits or gashes 12—12 and 13—13 etc., in the outer surface of the stiffeners oblique to the planes of the surfaces of the stiffeners. As shown, the slits are curved and the curves are convex toward the direction in which the blank 25 is drawn about the last.

As shown, the incisions 12 are formed in the middle of the counter blank, which is the back of the shoe, and are curved in opposite directions on either side of the centre, each set of cuts being substantially parallel. The two sets of incisions 13 are located respectively in the wings of the counter adjacent to the cuts 12. I prefer to extend the cuts only part way through the counter blank, as shown, but they may be extended entirely through to form slits, if desired.

The toe stiffener 30 consists of an amply heavy leather or fibre blank skived and contoured in the usual manner and having incisions 31—31 formed therein to extend angularly inward, in 40 all respects similar to the cuts 12 and 13 formed in the counter blank.

The blanks thus prepared are then wetted or tempered and a coat of adhesive 15, such as the usual shoemaker's paste, is applied to both surfaces of the respective blanks and to the facing surfaces of the upper 17 and lining 18 of the shoe, whereupon the blanks are inserted in interlining relation between the upper and lining, as indicated in Figure 6.

The upper parts, including the reinforcements, are then conformed to a last 20 on which the shoe is assembled in the usual manner, the wings of the counter blank being drawn forwardly and 55

the margins of the upper, lining and reinforcements being pulled over the last and secured to a sole member 21 by means of tacks 22 or other suitable means.

5 It will be found that the top line and bottom line of the counter stiffener will conform closely to the last with very little shirring or plaiting, because the intermediate slotted portions of the stiffener will give or stretch slightly and the 10 slits will open up to provide roughened surfaces, obtaining a firm bond with the paste which flows into the slits. When the paste congeals, it serves to restiffen the construction and hold it in its lasted shape.

15 All of the shoemaking operations shown referred to are customary and usual except for the formation of the incisions in the fibrous reinforcing parts. Also, the further operations necessary to complete the shoe may be the same as are 20 customarily performed in making turned, McKay or welted constructions and no detailed description of such shoemaking practices are necessary for a complete disclosure of my present invention.

25 Reinforcements for counters and toes are usually manufactured separately and sold to the shoemaker either in flat blanks or premolded substantially to the size and conformation required for the shoe. Stiffeners having my improved construction may be similarly premolded, if desired, without sacrificing any of the advantages here taught.

30 The shoe embodying my improved stiffeners is strong and comfortable and the top line and 35 bottom line at the counter portion maintain their shape and show no tendency to sag or break down. The weight of the counter reinforcement being adequate, there is ample strength and stiffness at the heel and quarter sections of the upper 40 while the weakening effect of the incisions over the areas of greatest strain robs the material of its elasticity at these points to such a degree that it cannot warp by reason of its tendency to resume its normal flat condition. Any such tendency is effectively further resisted by the congealed paste filling the interstices between the 45 margins of each incision and reinforcing the construction. (See Figure 9.)

50 It will be clear from the foregoing disclosure that shoes of different styles made on different lasts may require toe counter reinforcing having a greater or lesser number of incisions which may extend at varying angles or be arranged in different relative positions. It is therefore desired that this disclosure be considered merely

illustrative of my invention as defined in the appended claims.

I claim:

1. A shoe comprising an upper and a lining therefor, a fibrous reinforcement interlined between said upper and lining, said reinforcement having a plurality of cuts formed in the outer surface thereof intermediate the top line and the sole of the shoe, certain of said cuts being located centrally of the reinforcement and extending approximately horizontal and other of said cuts extending approximately vertical and located forwardly of the horizontal cuts, and adhesive bonding the outer surface of the reinforcement to the inner surface of the upper, said adhesive extending into said cuts. 15

2. A shoe comprising an upper and a fibrous reinforcement lining said upper, said reinforcement having a plurality of open scores formed therein extending angularly inward from the outer surface thereof intermediate the top line and the sole of the shoe, said cuts being located centrally of the reinforcement and extending substantially horizontal, and adhesive bonding the outer surface of the reinforcement to the inner surface of the upper, said adhesive extending into said scores. 20

3. A shoe comprising an upper and a fibrous reinforcement lining said upper, said reinforcement having a plurality of curvilinear incisions formed therein extending angularly inward from the outer surface thereof over the greater portion of a central area intermediate the top line and the sole of the shoe transversely of the back seam of the shoe, and adhesive bonding the outer surface of the reinforcement to the inner surface of the upper, said adhesive extending into the incisions. 30

4. A shoe reinforcement of the character described comprising a fibrous sheet having a plurality of curvilinear scorings formed in a surface thereof over the greater portion of a central area intermediate opposite margins, the curves of the scorings on opposite sides of the centre of the sheet being convex in the direction of the adjacent margins of the sheet. 40

5. A reinforcement for the toe portion of a shoe comprising a contoured blank of fibrous sheeting having a plurality of curved cuts formed therein over the greater portion of the central area intermediate the margins the curves of said cuts on opposite sides of the centre of the blank being convex in the direction of the adjacent margins of the blank. 50

EDWARD QUINN. 55
